UNITED STATES PATENT OFFICE.

HARRY CHILINGIRIAN, OF BRIDGEPORT, CONNECTICUT.

WRITING SET AND INKSTAND.

Application filed February 14, 1922. Serial No. 536,513.

To all whom it may concern:

Be it known that I, HARRY CHILINGIRIAN, a citizen of Armenia, residing at Bridgeport, county of Fairfield, State of Connecticut, have invented an Improvement in Writing Sets and Inkstands, of which the following is a specification.

This invention relates to writing sets or cabinets and has for an object to provide a simple and neatly appearing cabinet to be placed on a desk or table to contain writing materials as paper, envelopes, ink, pen, blotter, and so forth, and will protect the same from dirt and injury.

It is a further object of the invention to provide a compact arrangement for holding such articles where they may be easily accessible.

With these and other objects in view, I have devised the structures illustrated in the accompanying drawings, in which—

Fig. 1 is a perspective view of the cabinet, open, in condition for use.

Fig. 2 is a transverse, central, sectional view thereof showing the rear compartment closed.

Fig. 3 is a view somewhat similar to Fig. 2 showing the rear compartment open.

Fig. 4 is a longitudinal, vertical, section through the forward half of the cabinet.

Fig. 5 is a partial sectional plan view.

Fig. 6 is a perspective, detailed view showing means for mounting the cover section for the forward compartment.

Fig. 7 is a perspective view of a release mechanism.

Fig. 8 is a perspective view of a modified construction.

Fig. 9 is a transverse section of the form shown in Fig. 8.

Fig. 10 is a view similar to Fig. 9 showing the cabinet closed.

Fig. 11 is a top plan view of the form shown in Fig. 8 with the cover sections removed.

Fig. 12 is a perspective view of a further modified form in open position.

Fig. 13 is a transverse section thereof.

Fig. 14 is a perspective view of a still further modification.

Fig. 15 is a transverse section of the form shown in Fig. 14.

Fig. 16 is a perspective view of a still further modification.

Fig. 17 is a transverse, sectional view thereof, and

Fig. 18 is a transverse section showing another slight modification.

Referring to Figures 1 to 7, the body of the cabinet comprises end walls 20 and front 60 and rear walls 21 and 22 respectively. A longitudinally extending, upright partition 23 divides the cabinet into forward and rear compartments 24 and 25, respectively. The rear compartment is preferably of greater height than the forward compartment to improve the appearance of the cabinet and to render the arrangement more convenient and the articles more accessible. The rear compartment is closed at the top by cover 70

26 hinged to the rear wall 22, and to the forward edge of this cover is hinged a second cover 27 for the forward half of the cabinet. The end walls of the cabinet, between the upper edge of the partition 23 and

the upper edge of the front wall 21 and the end walls 28 of the cover section 27, are given corresponding shapes as shown, so that, when the cover section 27 is closed down to the dotted line position shown in 80

Fig. 2, the cabinet will be rectangular in shape. Carried within the cover section 27, are suitable pen and pencil racks 29. I also preferably mount a bar 30, spaced from the rear wall 31, to provide holding means for 85 paper or other articles. Within the rear compartment 25, is a receptacle 32. As it

is desired to place articles in this receptacle but still have them easily accessible, this receptacle is mounted to be vertically movable so that, when the cabinet is closed, the receptacle is at the lowest part of rear compartment 25, but it is so connected with the cover 26 that, upon raising this cover to gain 90

access to the compartment, the receptacle 32 will be raised leaving any articles in the receptacle where they may be easily reached. I have shown a connection which I prefer.

In the present instance, a pair of plates 33 provided with a series of holes 34 being secured by any suitable means to the underside of the cover 26. Suitable links 35, connected at one end to the receptacle 32, may be connected at their other ends to any of the holes 34. It will be apparent that raising of the cover 26 from the position shown in Fig. 2 to that shown in Fig. 3, will raise 100

the receptacle 32 to a position at the upper part of the compartment 25.

In order to lock the cover 26 closed, I provide spring catches 36 located in recesses 37 in the side-walls of the compartment 25

110

and provide it with projections 38 adapted to extend over the upper edge of the sides of receptacle 32 when it is in its lowest position and retain it therein, a suitable 5 spring 39 being provided between the bottom of the rear compartment and the top of this spring to flex the same and move the projections 38 over the edge of the receptacle. In the lower part of the cabinet, 10 mounted on suitable guides 40, is a drawer 41 adapted to be drawn out forwardly by means of suitable handles 42. I provide, within this drawer, means for releasing the spring catch 36 which comprises a rod, 43 15 pivoted in the drawer and extending transversely at the bottom thereof, and having its opposite ends bent at right angles as shown at 44 and 45. The front end 44 has pivotal connection with a link 46 pivoted 20 at its other end to a crank 47 on a pin 48 mounted to turn in the forward wall of the drawer and connected with one of the handles 42 whereby it may be rotated. The rear end 45 is so located that, when it is in 25 an upright position as shown in Figs. 3 and 7, it is in alignment with the bottom portion of spring catch 36. Therefore, in order to release the receptacle 32, the handle is rotated when the drawer is closed to bring 30 the rear end 45 to an upright position. The drawer then is drawn outwardly, as shown in Fig. 3, and the upper end of the bend 45 flexes the lower portion of the spring catch 36 upwardly withdrawing the projections 38 from a position over the receptacle 32 35 into the recesses 37. Cover 26 may now be lifted raising the receptacle 32 to the position shown in Fig. 3. As the walls of the spring catch are tapered above the projections 38, lowering of the cover 26 and receptacle 32 will press the catch back into the recesses and the projections 38 will spring out over the receptacle automatically 40 when it reaches its lowest position.

45 The space of the forward compartment 24 is preferably occupied by ink-stands, blotters, paste-rolls, and like articles. I preferably cover this compartment with three sections 49, 50, and 51 which are mounted, as 50 indicated in Fig. 6. The partition 23 is provided in its front wall with a horizontal groove 52 and the front wall 21 is provided on its rear side with a corresponding groove 53, there, however, being provided a recess 54, preferably in the middle length thereof, leading to this groove and of a length equal to or greater than the longest section 49, 50 and 51. The sections are provided with corresponding ribs 55 and are placed in 55 position by inserting sections 49 and 51 through the recess 54, then sliding them laterally. Mid-section 50 will rest between the other two sections as shown in Figs. 1 and 4. As the mid-section is easily removable, I 60 mount on the underside thereof some article

that is used relatively often, such as a blotter. In the form shown, I employ a U-shaped bracket 56 in which is mounted two rolls 57 to which the blotting paper may be secured in any suitable manner. I may, however, use other forms of blotter securing means, if desired. In the front wall 21, is an opening 58 in which a drawer 59 is slidably mounted, this drawer being located beneath the mid-section 50 and it will be noted from an inspection of Fig. 2, that the rear wall 60 thereof is of such a height as to extend above the lowest part of the blotter support so that, when the section 50 is in position, the drawer cannot be opened. Section 50 is provided with any suitable handle 61 to facilitate removal of this section and use of the blotter. 70 Sections 49 and 51 are provided with openings 62 through which the neck of an ink-bottle 63 may project, and are provided with suitable covers 64 therefor. The ink-bottles are held in position against the under wall of the sections with their necks in the openings by means of supporting platforms 65 suspended from the sections 49 and 51 by means of coiled springs 66, suitable hooks 67 being provided to connect the ends of the springs to the sections and support 65. It will be evident these supports 75 retain the necks of the ink-bottles in the openings 62 and allow depression of the platforms 65 to allow removal and insertion of the bottles. If preferred, these springs may be located beneath the platform resting on suitable supports. 80

The walls are preferably joined together by suitable tongues and grooves, as shown at 68, or the end of one wall may be let into a groove in the wall to which it is joined, as shown at 69. I do not wish to be limited to these forms of joints, however, as any suitable joint may be employed. 85

Referring to the modification shown in Figs. 8 to 11, this form includes the end wall 70, rear wall 71, and front wall 21 as in the form shown in Fig. 1. The front compartment, however, is formed with the front wall 21 by interior end and rear partitions 72 and 73 parallel with the end and rear walls 70 and 71 and spaced inwardly therefrom a short distance, as shown in Fig. 11. The compartment is covered by the sections 49, 50 and 51 mounted the same as the form illustrated in Figs. 1 to 7 and which support the same articles in the same manner. In other words, the forward compartment of this form is the same as the forward compartment of the preferred form. The compartment is closed, however, by a cover 74 adapted to be moved from a horizontal position, as shown in Fig. 10, to a vertical position between the rear walls 71 and 73, as shown in Figs. 8, 9 and 11. A suitable drawer 75 is mounted beneath the 90 95 100 105 110 115 120 125 130

front compartment and may have suitable racks 76 for pens and pencils. Within the spaces between the end walls 70 and 72, are mounted grooved pulleys 77 two in each space, one at the upper rear portion thereof and the other at the lower forward portion, as shown in Figs. 9 and 10. Suitable cords 78 connect the rear end of the cover 74 to the rear end of the drawer, and the cover is 5 provided with hooks 79 so arranged that, upon movement of the drawer to open position shown in Fig. 9 to closed position shown in Fig. 10, the string will raise the cover until the hooks engage the rear pulleys 77, when the cover will swing down to the horizontal position shown in Fig. 10.

In the modification shown in Figs. 12 and 13, the construction is slightly different from that shown in Fig. 1. The forward 20 compartment is the same except that, instead of using two ink-bottles, one section 51 may be provided with a paste-roll 80, and the cover 81 for the forward compartment, instead of being hinged to the cover 25 26 for the rear compartment 25, is hinged at the upper edge of the front wall 21. The drawer 41 is also omitted in this form.

In the form shown in Figs. 14 and 15, the hinged covers are omitted but the compartment for the ink-bottles and the blotters is covered by sections 49, 50 and 51 the same as the form shown in Fig. 1. That is, the same compartment is used for both forms including the drawer 59. Suitable racks 82 are provided forwardly of the compartment for pens and pencils and there is also a suitable drawer 83 in the lower part of the cabinet.

In the form shown in Figs. 16 and 17, the drawer in the lower part of the cabinet is omitted, but the compartment for the ink-bottles and blotter is located in the forward part of the cabinet, and comprises the same elements as does the corresponding compartment in the form shown in Fig. 1. The rear compartment 84 in this form is closed by hinged cover 85 carrying pen and pencil racks 86.

The modification shown in Fig. 18 is somewhat the same as that shown in Figs. 12 and 13 except that the cover 26 for the rear compartment 25 is omitted, but the forward cover 87 which is hinged to the upper edge of the front wall 88 is of a width equal to the width of the body of the cabinet, and its end walls 89, when it is in open position, are in alignment with the end walls 90 of the body, so that, when the cover is moved to closed position as shown in dotted lines, the cabinet will be rectangular in form. The forward compartment 91 is constructed the same as the forward compartment in the form shown in Figs. 12 and 13, and the cover carries the pen and pencil racks 86.

Having thus set forth the nature of my invention, what I claim is:

1. In a writing cabinet walls forming a compartment open at the top thereof, the walls on opposite sides of said compartment being provided with longitudinally extending grooves, one of said walls also having a recess leading downwardly to its groove, and sections for closing the top of said compartment having ribs 70 adapted to slide in said grooves, said sections being adapted for insertion into the grooves at said recess and then slidable laterally therefrom.

2. In a writing cabinet walls forming a 80 compartment open at the top thereof, the walls on opposite sides of said compartment being provided with longitudinally extending grooves, one of said walls also having a recess leading from the top thereof to its groove, sections for closing the top of said compartment having ribs adapted to slide in said grooves, said sections being adapted for insertion into the grooves at the recess 85 and then slidable laterally therefrom, a third section adapted to rest in the recess, a drawer beneath the third section and adapted to be drawn forwardly through the front wall, and means projecting downwardly from said section to engage the drawer to prevent withdrawal thereof when the section is in position.

3. In a writing cabinet walls forming a 90 compartment open at the top thereof, a vertically movable receptacle in said compartment, a hinged cover for closing the open top of said compartment, a connection from the cover to the receptacle whereby the receptacle is raised on raising the cover, securing means for holding the receptacle 95 in lowered position, a drawer in the cabinet, and means carried by the drawer and accessible for operation at the front thereof for controlling the securing means.

4. In a writing cabinet walls forming a 100 compartment open at the top thereof, a vertically movable receptacle in said compartment, a hinged cover for closing the open top of said compartment, a connection from the cover to the receptacle whereby the receptacle is raised into said opening on raising the cover, spring actuated securing means for holding the receptacle in lowered position, a drawer in the cabinet, means carried by the drawer for controlling the 105 securing means and movable at will to operative and inoperative positions, and means accessible from the exterior of the drawer for so moving said controlling means.

5. A writing cabinet comprising end and side walls, a longitudinal partition between the side walls forming compartments open at the top thereof, means for supporting receptacles in the forward compartment, a 115 hinged cover for the open top of the rear 120 compartment, and a drawer in the cabinet, means 125 carried by the drawer for controlling the securing means and movable at will to operative and inoperative positions, and means accessible from the exterior of the drawer for so moving said controlling means.

compartment, a cover for closing the forward compartment hinged to the first named cover, and article supports carried by the second cover on the inside thereof so that they are enclosed in the cabinet when the cover is closed, said second cover being arranged to fold back on first cover to expose said supports.

6. In a writing cabinet walls forming a compartment open at the top thereof, a vertically movable receptacle in said compartment, a hinged cover for closing said compartment, a connection from the cover to

the receptacle whereby the receptacle is raised into said opening on raising the cover, securing means for holding the receptacle in the cabinet, a drawer in the cabinet, means carried by the drawer for controlling the securing means and movable at will to operative and inoperative positions, a handle for said drawer, and means connecting said handle with the controlling means to operate the same.

In testimony whereof I affix my signature.

HARRY CHILINGIRIAN.
